US0D1062420S

(12) **United States Design Patent** (10) **Patent No.:** **US D1,062,420 S**
(45) **Date of Patent:** **** Feb. 18, 2025**

(54) **MULTITOOL**

(71) Applicant: **Richard Joseph Myers**, Worthington, PA (US)

(72) Inventor: **Richard Joseph Myers**, Worthington, PA (US)

(**) Term: **15 Years**

(21) Appl. No.: **29/843,019**

(22) Filed: **Jun. 17, 2022**

(51) **LOC (15) Cl.** **08-05**

(52) **U.S. Cl.**

USPC **D8/105**

(58) **Field of Classification Search**

USPC D8/14, 26, 34, 87, 88, 89, 105

CPC B25F 1/00; B25B 15/007

See application file for complete search history.

(57) **CLAIM**

The ornamental design for a multitool as shown and described.

DESCRIPTION

FIG. 1 is an isometric view of the multitool in extended position.

FIG. 2 is a front view thereof in extended position.

FIG. 3 is a back view thereof in extended position.

FIG. 4 is a side view thereof in extended position.

FIG. 5 is a side view thereof in extended position.

FIG. 6 is an end view thereof.

FIG. 7 is an end view thereof; and,

FIG. 8 is an isometric view thereof in a retracted position. The broken lines are included for the purpose of illustrating portions of the multitool and form no part of the claimed design.

1 Claim, 5 Drawing Sheets
